CONTAINER

Henry M. Dillhoefer, Jr., Cleveland Heights, Ohio

Application July 23, 1932, Serial No. 624,163

1 Claim. (Cl. 220—39)

This invention relates to a container, more particularly to the closing means therefor, whereby the container may be advantageously used for shipping and storing liquids and semi-liquids. 5 The closing means is, for illustrative purposes, shown applied to one wall of a container fabricated from sheet metal. The container herein shown is provided with two openings both of which are preferably provided with my improved closing means, but where desired, one opening 10 may be otherwise closed; also, either opening may, when desired, be formed in the side wall or body portion of the container instead of its head.

In container constructions, the filling openings 15 therefor have usually been closed, after the containers are filled, by screw threaded plugs, each having a flange which was utilized to engage a gasket when the plug was tightened and thus make the opening liquid tight. Plugs of this 20 type have been found objectionable because they project a considerable distance above the container wall and much difficulty has been experienced in effectively providing for the mechanical sealing of such plugs against access to the 25 container without detection.

In attempting to overcome these difficulties, the closure plugs have been formed with tool 30 receiving sockets, the flanges of the plugs have been substantially eliminated and the side walls of the plug and its receiving bung ring, either or both, have been rabbeted or recessed to receive a gasket to insure liquid tightness. In this arrangement obviously much care must be exercised to correctly position the gasket.

One object of the invention is to provide an 35 improved closure so constructed and related to the walls of the bung ring that the opening through the latter may be sealed in a liquid tight manner and the closure may fit entirely within the ring, whereby danger of the plug extending above the container chime is avoided.

Another object of the invention is to provide a 40 headless closure so constructed that it may be mounted in the container opening in such manner that the opening is sealed against leakage without the use of a gasket.

Another object of the invention is to provide 45 for the opening in the wall of a container, an improved closure means which is relatively simple and of minimum height and which permits of the application of a multilatable or removable cap that may be utilized as an auxiliary sealing device and as a surface for the application of desired insignia.

50 Other objects of the invention will be appar-

ent to those skilled in the art to which my invention relates from the following description taken in connection with the accompanying drawings, wherein

Fig. 1 is a perspective view of a container embodying my invention, parts being broken away. 5

Fig. 2 is a plan view, parts being broken away.

Fig. 3 is a section on the line 3—3 of Fig. 2.

Fig. 4 is a fragmentary sectional view, enlarged. 10

Fig. 5 is a sectional view of the plug.

Fig. 6 is a sectional view of a plug of modified construction.

Figs. 7 and 8 are fragmentary sections but showing different embodiments of the invention. 15

Fig. 9 is a section on the line 9—9 of Fig. 8.

In the drawings, 1 indicates as an entirety a container, preferably having a sheet metal body portion 1a and heads 2, 3. For illustration purposes, the body portion is formed of a sheet metal 20 section having its longitudinal edges suitably united in sealed liquid tight relation. The ends of the body and peripheral edges of the heads are suitably united, for example, by a double seamed joint, in a liquid tight manner. The container 25

1 is formed with one or more openings and each may be formed in the body portion or in either head. By preference, I show two openings in the head 3. Where two openings are provided, both are sealed in a liquid tight manner, as herein- 30 after set forth, and when desired, the closure may be covered by a cap, the surface of which may carry suitable insignia, and such cap may be utilized as a detection means to prevent unauthorized access to the contents of the container, so 35

that I provide for a liquid-tight seal and a mechanical seal. Where the liquid-tight seal only is employed, the bung ring may be mounted in its opening in either upright or inverted position, but where the mechanical seal is to be applied, 40 the bung rings of the form shown in Figs. 1, 2, 3, 4 and 8 are inverted for reasons which will later appear.

For illustrative purposes, I have shown both 45 openings in the head 3 sealed in both a liquid-tight manner and against unauthorized opening by similar means, but in the following description I will refer to one opening and the closing sealing means therefor: 5 indicates an opening formed in the head 3. 6 indicates a bung ring fixedly associated with the opening and threaded internally to receive the closing element 4. 7 indicates an annular shoulder or wall spaced from the upper face of the head 3 in concentric relation to the opening 5. The wall 7 preferably consti- 55

tutes an annular shouldered portion resulting from the application and mounting of the bung ring 6 in relation to the opening 5, thereby avoiding a specially constructed shoulder on the head or ring. For this purpose I show in Figs. 1, 2, 3 and 4 a pressed-in bung ring 6 preferably similar to that shown in the co-pending application of Henry M. Dillhoefer, Ser. No. 486,018 (see Letters Patent No. 1,929,412, dated October 10, 1933), except that the ring 6 is mounted in an inverted position. The ring 6 comprises an internally threaded body portion 9 fitted into the neck 10 of the head or wall 3 and having at one end a flange 11 seated and incorporated in the wall of the head 3 and at its other end a circumferentially extended portion beaded over the free end of the neck 10, such beaded over portion forming the annular shoulder 7; in Fig. 7 I show a pressed-in bung ring 6' of the construction shown in Letters Patent No. 1,783,927, granted to Theo. W. Rieke and comprising an internally threaded body portion 9a having at one end a flange 11a, the metal of the head 3' engaging the outer and inner faces of the flange at 12, 13, and extending around the periphery of the flange, as shown at 1a, to form the annular shoulder in spaced relation to the upper face of the head 3'; and in Figs. 8 and 9 I show a pressed-in bung ring 6x substantially similar to that shown in my co-pending application Ser. No. 492,790 and comprising an internally threaded body portion 9x having external tapered flat side walls fitting into a correspondingly shaped neck 10x provided on the head 3 and a circumferential portion at one end beaded over the free end of the neck 10x and forming a shoulder 1x.

In the forms of construction shown each of the bung rings is provided internally with V-straight pipe threads and such threaded wall extends in a direction parallel to the axis of the ring, whereas the closure element is provided with V-tapered pipe threads of the same pitch as the ring. Rings of $\frac{3}{4}$ inch size are provided with a 14 pitch thread; rings of $1\frac{1}{2}$ and 2 inch size are provided with an $11\frac{1}{2}$ pitch thread; also, either the internal pitch diameter of the ring 6 is slightly smaller than the pitch diameter of the larger end of the closing element 4 or the pitch diameter of the latter is slightly greater than that of the ring, the purpose being to effect a sealing relation between the inter-engaging threads of the ring and plug when the latter is screwed into tightened position. By preference, the difference in diameter may be approximately two thousandths of an inch. As a result of this arrangement, when the element 4 is screwed into position and tightened, the interengaging threads of the bung ring and element bite into each other, and produce an expanding force on the thread walls of the ring. The walls of the inter-engaging

threads are thus forced into such close relation that they effect a liquid tight seal between the ring and closure element. Accordingly, the element 4 may be made headless or flangeless, as shown, and no gasket is required between the 5 closure and ring to insure liquid tightness. In this arrangement, less metal is required for the manufacture of the plug, which reduces its cost and also its weight for shipping purposes. In actual manufacture I prefer to increase the pitch 10 diameter of the closing element slightly, so that the ring 6 will adapt itself to a conventional closing plug when the latter is to be used.

The arrangement also provides (1) a closing element having its top surface in or below the 15 plane of the exposed end of the bung ring or metal of the head engaging therewith and (2) for the ready application of a mechanical seal of relatively simple construction, such as a cap 14 crimped around the wall 7 (or 1a or 1x). The 20 cap 14 is formed of relatively thin metal and has a circumferential flange adapted to be crimped into locked relation to the wall 7 or 1a or 1x by a suitable tool, so that the removal of the cap can only be effected by its mutilation, and un- 25 authorized access to the container contents or attempted access will be readily detected, since the cap cannot be replaced and re-conditioned to give it its original appearance. By using a gasket, as shown at 15, the cap may form an 30 auxiliary liquid tight seal.

In my form of construction the closing element 4 may be removed and replaced as often as desired, but in case it becomes lost, the ring 6 is adapted to receive a conventional plug. 35

To those skilled in the art to which my invention relates, many changes in construction and widely differing embodiments and applications of the invention will suggest themselves without departing from the spirit and scope of the in- 40 vention. My disclosures and the description herein are purely illustrative and are not intended to be in any sense limiting.

What I claim is:

A liquid-tight closure for a container, comprising a bung ring seated in the wall of the container the internal wall of the said ring being parallel to its axis and provided with V-pipe threads and a plug adapted to have screw-threaded engagement with the said ring, the external wall of the plug tapering slightly and having formed therein V-pipe threads, the internal diameter of the threads in the plug at its larger end being greater than the internal diameter of the threads in the ring, whereby when the plug is set tightly into the ring a liquid-tight closing of the opening into the container is produced without the necessity of gasket or other closing elements additional to those specified.

HENRY M. DILLHOEFER, JR. 60
